ATTY

UNITED STATES PATENT OFFICE.

BURR V. DEITZ, OF SLINGERLANDS, NEW YORK.

WIRELESS-TELEPHONE APPARATUS.

1,214,655.

Specification of Letters Patent.

Patented Feb. 6, 1917.

Application filed October 15, 1913. Serial No. 795,384.

To all whom it may concern:

Be it known that I, BURR V. DEITZ, a citizen of the United States of America, residing at Slingerlands, in the county of 5 Albany and State of New York, have invented certain new and useful Improvements in Wireless-Telephone Apparatus, of which the following is a specification.

My invention relates to wireless apparatus, and the object of my invention is to provide a compact, quickly assembled, easily regulated and highly sensitive means for receiving aerial messages, and a means for changing alternating to a direct current; together with such elements and combinations as are hereinafter more particularly set forth and claimed. I accomplish these objects by means of the mechanism illustrated in the accompanying drawings, in which:

20 Figure 1 is a plan. Fig. 2 is a side elevation. Fig. 3 is an end elevation of my apparatus. Fig. 4 is a diagrammatic view of the wiring therein.

Similar letters and numbers refer to similar parts throughout the several views.

25 A box, A, provided with a cover, B, side pieces, C, and bottom, D, supports and contains in a compact compass all of the apparatus necessary for an efficient wireless receiving apparatus.

On the cover, B, I mount the coil, 1, and the secondary coil, 2, adapted to be reciprocated within coil, 1. The frame, F, carries the reciprocating contact, 3, the frame containing the wire, 4, leading to ground, G. I also carry on the cover, B, the switches, 35 M and O, and the detectors, H and J. On the side of the box, I arrange the switches, 7, 8 and 9, connected with the wiring in the box. The secondary coil, 2, is regulated by a switch, 10, on the end thereof adapted to be connected with the contacts, 11, which are respectively connected with segments of the winding on the secondary coil.

40 K, represents the aerial from which the current is led to the apparatus.

The construction of my apparatus provides for conducting from the aerial, K, a high frequency alternating current, which 45 passes through the wires, 17 and 12, switch, 7, wire, 13, to condenser, 15, and coil, 14, through the coil, 14, and through wire, 16, to coil, 1, and from coil, 1, through wires, 3 and 4, to ground, G. The wire, X, leads from 50 the condenser to wire, 4, to ground. An inductive high frequency current is produced

in coil, 2, and passes from thence through wire, 22, to condenser, P, thence to wire, 23, to detector, H; through detector, H, wire, 30, switch, 8, wire, 21, to coil, 2.

60 The detector, H, is a voltaic cell comprising three minerals, to wit: ore of copper or iron, zinkite, or red oxid of zinc, with fused silicon interposed between. The low voltage current formed in the detector will escape 65 during the action of the high frequency inductive current through the wire, 30, switch, 8, wire, 21, coil, 2, wire leading to telephone, T, to wire, 23, at end, and back to detector, H. There is thus delivered to the telephone 70 a direct current which will render audible the impulse of the high frequency alternating current received through the aerial system.

75 The arrangement of the coils, 1 and 14, and condenser, 15, is such that they may be varied to make their circuit in resonance with the transmitted wave. The means for performing this regulation is not the subject of this invention, although it is illustrated 80 in Figs. 1, 2 and 4 and will be readily understood.

85 The arrangement of the detectors, H and J, which are constructed alike, is such that either one or the other may be used, depending upon the position of the switch, 8. My invention relates to a detector which is constructed of three minerals and forms a voltaic cell, as hereinbefore stated, and which, so far as I know, is new in the art. I am 90 aware that chalcopyrite, iron pyrites, zinkite and silicon have each been used in detectors heretofore, but never, so far as I know, have they been used together for the purpose of forming a detector by the formation of a voltaic cell in which two minerals,—chalcopyrite and zinkite, are separated by silicon for producing a direct low voltage current which is capable of operating an electromagnet, and which is automatically 95 caused to flow during the flow of high frequency current through the detector, and which ceases to flow when the high frequency current ceases to flow through the detector.

100 I believe that the low voltage direct current is formed in the detector, either by chemical action or otherwise; that the low voltage current is of a low constant value, because the resistance of the silicon forming 110 an internal high resistance within the cell is only overcome by the aerial current, the

direct current being allowed to flow during the flow of the aerial current. I find that any electrical aerial disturbances, such as aerial or static electricity, or electric wave impulses, are reproduced very accurately by this detector. Each fluctuation or change of amperage of the high frequency current is reproduced in direct current by the detector, so that electric oscillatory currents carrying 10 impressions of the human voice are clearly reproduced.

What I claim as my invention and desire to secure by Letters Patent is:

1. A detector for wireless signals, comprising the minerals fused silicon, zinkite and ore of copper, together forming a simple voltaic cell.

2. A detector for wireless signals, comprising the minerals zinkite, silicon and pyrites of any kind. 20

3. A detector for wireless signals, comprising a mass of zinc oxid held firmly in a cup; a piece of chalcopyrite held firmly in another cup, with their rough surfaces extending toward each other, the cups movable and adjustable, having a mass of silicon clamped between the two. 25

In testimony whereof I have affixed my signature in presence of two witnesses.

BURR V. DEITZ.
